(57) **CLAIM**

The ornamental design for a convertible medical sponge counter bag, as shown and described.

DESCRIPTION

FIG. 1 is a rear perspective view of the convertible medical sponge counter bag, showing five transparent pockets;
FIG. 2 is a front perspective view thereof, showing ten pockets with a center seal pocket divider;
FIG. 3 is a rear elevation view thereof; showing five pockets;
FIG. 4 is a right side elevation view thereof; the left side being a mirror image;
FIG. 5 is a front plan view thereof; showing ten pockets;
FIG. 6 is a top plan view thereof; and,
FIG. 7 is a bottom plan view thereof.
The broken lines form no part of the claimed design.
